GAME

Alfred H. Behrman, Baraboo, and Franklin H. Avers, Portage, Wis., assignors to George E. Sinclair, Juneau County, Wis.

Application January 12, 1933, Serial No. 651,312

16 Claims. (Cl. 273—121)

This invention appertains to games, and game apparatus, and more particularly to games of the type in which a predetermined number of balls or like projectiles are released upon the depositing of a suitable coin, so that the same can be shot one at a time by a player on to a playing board having counting pockets, or the like.

One of the primary objects of our invention is to provide a game of the above character, which will provide a maximum amount of amusement for the players, and hold their attention during the playing of the entire game, novel means being provided wherein the players are permitted to withdraw certain selected balls from the playing board, after the initial projecting thereof, so that these balls can be replayed in an effort to increase the score.

Another salient object of our invention is to provide a game which can be played along the lines of a conventional card game, the players initially projecting five balls, one at a time, on to the playing board having pockets or traps designated by cards of a deck of playing cards, the points of rest of the balls constituting the player's hand, means being provided wherein the player can "draw" to his hand in an effort to increase the value thereof, by selectively withdrawing the desired balls from the pockets or traps to permit replaying thereof.

A further important object of our invention is to provide a game apparatus embodying a playing board, with means for projecting balls or the like over the playing board with means including a gate for controlling the passage of the balls to the projecting device, said gate being so arranged as to allow the balls to pass therethrough twice before the closing and locking thereof, whereby the players are permitted to initially project the balls over the board, and then replay the desired balls in an effort to increase their score.

A further important object of our invention is to provide a coin-controlled game apparatus, in which the balls are released upon the depositing of a suitable coin, the releasing means being automatically re-locked after the balls have passed through said means a predetermined number of times.

A further object of our invention is to provide novel means wherein a player can release any desired ball from a counting pocket or trap, means being also provided for simultaneously releasing all of the balls from the pockets or traps upon the depositing of the appropriate coin.

A further important object of our invention is the provision of a novel ball carrier movable

from the ball-releasing means to the ball-projecting means, the ball-releasing means being initially actuated by the player upon the operation of the ball-selecting means from the counting pockets or traps, and finally actuated by the ball carrier upon the second operation of said carrier for automatically re-locking the ball-releasing means.

A further object of our invention is the provision of means for simultaneously releasing the balls from the playing board and for unlocking the ball-releasing means upon the depositing of the appropriate coin, so that the game will be ready for instant playing after the depositing of the said coin.

A still further object of our invention is to provide an improved game of the above character, which will be easy to operate, and which can be placed upon the market at a reasonable cost.

With these and other objects in view, the invention consists in the novel construction, arrangement, and formation of parts, as will be hereinafter more specifically described, claimed, and illustrated in the accompanying drawings, in which drawings:

Figure 1 is a top plan view of our improved game, with parts thereof broken away and in section to illustrate structural details.

Figure 2 is an enlarged detail section taken on the line 2—2 of Figure 1, looking in the direction of the arrows, illustrating the means for actuating the initial gate-releasing means for the balls from the ball selector.

Figure 3 is a top plan view of the detent for the gate, which is actuated from the ball selector.

Figure 4 is a transverse section through the game, taken on the line 4—4 of Figure 1, looking in the direction of the arrows, and illustrating the means employed for selectively releasing the balls from the counting traps or pockets.

Figure 5 is a detailed fragmentary section taken on the line 5—5 of Figure 1, looking in the direction of the arrows, illustrating the means for simultaneously operating the ball-controlling gate and the ball-releasing means of the playing board from the coin-controlled mechanism.

Figure 6 is a transverse section through the game taken on the line 6—6 of Figure 1, looking in the direction of the arrows, illustrating a part of the gate-controlling mechanism, the gate being shown in its raised position and held against movement by both of the locking mechanisms.

Figure 7 is a detail section taken in front of Figure 6, illustrating the ball carrier, the carrier

being shown in full lines in its raised position, and in dotted lines in its lowered ball-receiving position.

Figure 8 is a view similar to Figure 7, with the ball carrier and projector removed to more clearly illustrate the mechanism employed for holding the ball-controlling gate in its raised position, the gate being shown engaged by both of the holding mechanisms.

10 Figure 9 is an enlarged detailed section taken on the line 9—9 of Figure 1, looking in the direction of the arrows, illustrating the construction of the playing board and a part of the ball-selecting mechanism.

15 Figure 10 is a detailed horizontal section taken on the line 10—10 of Figure 4, looking in the direction of the arrows, illustrating a part of the ball-selecting mechanism.

20 Figure 11 is a transverse section through the ball run-way, looking toward the gate and the gate-holding mechanism.

25 Figure 12 is a detail section taken on the line 12—12 of Figure 1, looking in the direction of the arrows, illustrating a part of the gate holding means.

Figure 13 is a view similar to Figure 8, showing the primary gate-holding means moved to its inoperative position.

30 Figure 14 is a view similar to Figure 13, showing both the primary and secondary gate-holding means moved to their released position, with the gate in its closed position.

35 Referring to the drawings in detail, wherein similar reference characters designate corresponding parts throughout the several views, the letter A generally indicates our improved game, which comprises a casing 15 which can be built in any preferred manner and ornamented in any desired way to enhance the appearance thereof. As shown, the casing 15 embodies front, rear, and side walls 16, 17, and 18. These walls can be braced in any desired way, and, as shown, a diagonal strut 19 is provided, which we extend from one corner of the casing to the other. 40 The top of the casing is closed by a frame 20, which carries a glass panel 21, whereby the playing board 22, located within the casing, can be readily seen by the players.

45 The playing board 22 is of a disc shape and is provided with a plurality of radially extending pins 24, which define pockets 25 in conjunction with a supporting table 26. Surrounding the playing board 22 is an annular race-way 27, and this race-way 27 includes a bottom wall 28 and an upstanding guard rail or wall 29. The pins 24 project toward the bottom wall 28 of the race-way and terminate short thereof, and the balls are adapted to be projected over the race-way toward the pockets 25.

50 By referring to Figure 4 of the drawings, it will be noted that the bottom wall 28 is inclined downwardly toward the pins 24 and the table 26, so that the balls will drop by gravity into the pockets. The pockets 25 can be indicated 55 by any preferred counting means, but, in accordance with our invention, the counting means are indicated by playing cards 30. An entire pack of cards, including the joker, is preferably utilized, and thus there is a total of fifty-three pockets.

55 In order to enhance the appearance of the game, the playing board 22, the race-way 27, and the table 26 can be covered with felt, or the like. As clearly shown in the drawings, certain 75 of the pins 24 are extended and are secured to

the bottom wall 28 of the race-way 27, the race-way forming a support for the playing board. The race-way in turn is rigidly held in place by supporting brackets 31, which are secured to the side walls of the casing or housing 15.

5 The table 26 is utilized for supporting the balls after the same have been projected on to the race-way 27, and we provide novel means for actuating this table so that the balls can be released and reconveyed to the projecting mechanism. We also construct the table in such a manner that the balls can be selectively released therefrom to permit re-playing of the balls during the playing of one game, as will be hereinafter more fully described. As shown, 10 the table 26 comprises a hub 32, spokes 33, and a connecting rim 34. The periphery of the rim is provided with radially projecting pins 35, for a purpose which will also be hereinafter more fully set forth. One of the spokes 33 is provided with a slot 36 which slidably receives the gate 37, which forms a part of the selective ball-releasing means. This gate extends to the periphery of the rim, and, when the same is in its closed position, constitutes a part of the rim. 15 Any desired type of means can be provided for slidably supporting the gate, such as brackets 38. A leaf spring 39 is employed for normally holding the gate in its closed position with the edge thereof in alignment with the periphery of 20 the rim.

Secured to the axial center of the playing board 22 is a hollow supporting post 40, and rotatably mounted within the post is a hollow shaft 41. This shaft 41 is provided with a head 42, which is in turn secured to the lower face of the table 26. Slidably mounted within the hollow shaft 41 is a plunger rod 43 having a plunger head 44 formed thereon, which extends below the lower face of the table. This plunger 40 head normally rests upon one arm of a bell crank lever 45, which is rockably mounted at an angle as at 46 upon a depending supporting bracket 47 secured to the lower face of the table. The upper arm of the bell crank 45 has pivotally secured thereto a link 48, which in turn is pivotally connected to the inner end of the gate 37. The plunger rod 43 extends above the hollow post 40, and has secured thereto a thumb-piece 49.

50 From the construction so far, it can be seen that upon depression of the plunger rod the bell crank 45 will be rocked, moving the gate inwardly against the tension of its spring 39. This will allow the releasing of a ball disposed upon the 55 gate. Secured to the hollow shaft 41 is an operating handle 50, and by turning the handle the table can be rotated so as to dispose the gate under any desired pocket, whereby the desired or selected ball can be released.

60 In order to indicate the position of the gate, a pointer 51 is provided. This pointer 51 can be of an arrow shape, and the head of the pointer extends in alignment with the gate. The inner end of the pointer is secured to a sleeve 52, which in turn is secured to the handle 50. The sleeve 52 is spaced from the shaft 41 and surrounds the hollow standard 40.

65 The transparent panel 21 is provided with an enlarged opening 53, through which extends the hollow standard 40 and a sleeve 52. An enlarged pad 54 surrounds the sleeve 52 and bears against the panel 21. If desired, this pad can be secured by a suitable cement to the panel, and the same 70

75

acts as a guard for the panel during the rotation of the sleeve.

The sleeve 52 and the hollow shaft 41 are mounted for sliding movement on the hollow standard, as well as for rotary movement, and in order to hold the table normally in a raised position, we provide a substantially U-shaped yoke 55. This yoke is secured to the lower face of the table 26 adjacent to its axial center, and the extreme lower end of the yoke normally rests upon a leaf spring 56. This leaf spring 56 is secured at one end to the baseboard or bottom wall 57 of the casing. The tension of the leaf spring 56 is such that the weight of the table will overcome the spring, and we provide releasable means for engaging the spring so that the table can be raised and lowered, as will now be pointed out.

Rockably mounted below the table is a lever 58, and this lever is supported for swinging movement by a pivot pin 59 connected with the diagonal strut 19. The inner end of the lever is provided with a wedge-shaped shoe 60, and by swinging the lever the shoe can be moved into and out of engagement with the spring. By referring to Figure 4 of the drawings, it can be seen that when the shoe is under the spring 56, the spring is moved upwardly to cause the raising of the table. When the shoe is moved away from the spring 56, the table will lower under the action of gravity and allow the balls to drop from the pockets.

The outer end of the lever 58 is provided with an angle arm 61, which extends to one side of the race-way 27. Secured to the arm 61 is an upstanding post 62, which extends through a slot 63 formed in the baseboard or bottom wall 57. The baseboard 57 is provided at its central portion with an opening 64, through which the yoke 55 extends so as to permit engagement thereof with the shoe 60. A guard rail 65 surrounds the opening so as to prevent the falling of the balls through the opening. By moving the post 62, the lever 58 can be readily swung on its pivot 59 for operating the shoe 60.

Located on the opposite side of the casing 15 from the lever 58 is the ball-projecting device 66. This ball-projecting device 66 may comprise a stationary tube 67 which is led through an opening 68 formed in the front wall 66 of the casing. The inner end of the tube 66 communicates with a substantially tangentially disposed inlet mouth 69, which in turn communicates with the race-way 27.

Slidably mounted within the tube 66 is a spring-pressed plunger 70, and this plunger is provided with a plunger rod 71, which is led exteriorly of the tubing 67 and the front wall of the casing. A finger-piece 72 is connected with the plunger rod, whereby the plunger can be drawn rearwardly against the tension of its spring to permit shooting of a ball over the race-way. An inlet opening 73 is formed in the tube 67 at a point intermediate its ends, so that the balls can be fed into the said tube.

In conjunction with the ball-projecting device, we utilize a novel ball-carrier 74. This ball-carrier 74 consists of a tubular receptacle having one end thereof closed and its other end open to permit the rolling of the balls into the same and the movement of the balls out of the same into the projector tube. Secured to the ball-carrier 74 is a rod 75. The end of the rod 75, remote from the ball-carrier 74, is rigidly secured to a hub plate 76, and this hub plate is rotatably

mounted on a supporting stud 77. A handle 78 is connected with the rod 75 intermediate its ends, and this handle extends through an arcuate slot 79 formed in the front wall 16 of the casing 15. The outer end of the handle can have a suitable finger-piece 80 connected therewith. The handle 72 for the ball-projector and the handle 80 of the ball-carrier are located in close proximity to one another, so that the player of the machine can conveniently actuate the same. A crank arm 81 is also connected with the rod 75, and a contractile coil spring 82 is secured to the crank arm and to the casing, whereby to normally hold the rod 77 and the ball-carrier 74 in an elevated position. It is to be noted that when the ball-carrier 74 is in its raised position, the open end thereof is lowermost and terminates at the opening 73 of the projector tube. Thus the balls from the carrier normally tend to gravitate into the said projector tube.

When the plunger is in its normal position, the spring prevents the flow of balls into the tube, but when the plunger is pulled inwardly past the opening a ball is permitted to roll into the tube. When the ball carrier 74 is in its lowermost position, the same communicates with an inclined run-way 83, and any balls on the run-way will be permitted to roll into the said ball-carrier.

Novel means is provided for preventing the balls from normally leaving the run-way, and this means forms an important part of the invention.

As clearly shown in Figure 6 of the drawings, the baseboard or bottom wall 57 is inclined toward the front of the machine so that the balls will tend to roll into the run-way as the same drop from the table 26. The means for controlling the passage of the balls from the run-way to the ball-carrier operates in conjunction with a coin-controlled mechanism 84, and this coin-controlled mechanism also actuates the post 62 for rocking the lever 58. The means for controlling the passage of the balls from the run-way 83 includes a gate 85. This gate 85 is formed on or secured to a swinging lever 86, which extends parallel with the front wall 16 of the casing. The opposite end of the lever 86 is rigidly secured to a shaft 87, which extends through one wall of the run-way 83. Secured to the same shaft 87 is an operating arm 88, and this operating arm extends toward the coin-controlled mechanism 84 and terminates adjacent to the post 62.

To limit the downward swinging movement of the gate 85 a hook-shaped finger 89 is formed on the lever 86, and this finger overlies the mentioned side wall of the run-way. Secured to the lever 86 intermediate the gate 85 and the finger 89 is a rigid keeper-plate 90. Formed on the upper end of the keeper-plate 90 is a keeper-hook 91 and a laterally extending cam finger 92. A hook-shaped latch arm 93 is rigidly connected with a swinging latch lever 94. This latch lever is rockably mounted on a pivot pin 95 rigidly secured to one wall of the casing. A contractile coil spring 96 is employed for normally moving the hook-shaped latch arm 93 toward and into engagement with the keeper-hook 91. Pivots mounted upon the latch lever 94 is a swinging dog 97, which is normally urged toward one side of the latch lever 94 by a leaf spring 98. A stop pin 99 is arranged in the path of the dog so as to limit the swinging movement thereof in one direction. It is to be noted that the lower end of the dog is disposed at an angle to the horizontal for a purpose which will be later set forth.

Operating in conjunction with the latch-plate 90 is another latch lever 100. The latch lever 100 constitutes the primary or initial locking means for the latch-plate 90 and gate 85, while the latch lever 94 and latch hook 93 constitute the secondary locking means for the gate.

Referring more particularly to Figures 2 and 3 of the drawings, it will be seen that the latch lever 100 is of a substantially bell crank shape, and has formed thereon intermediate its ends a hub sleeve 101, which is rockably mounted upon a supporting pin 102 secured to the lower face of the race-way 27. The inner end of the latch lever constitutes a trip arm, as indicated by the reference character 103. The opposite end of the latch arm is provided with a rigid latch pin 104, which is adapted to be moved under the laterally extending keeper finger 92 of the keeper-plate 80.

20 The upper face of the latch lever 100 has connected therewith an eye 105, to which is secured one end of a pull cord 106'. This pull cord 106' extends across the front of the machine in the rear of the front wall 16, and a suitable guide-eye and the like is provided for supporting the cord. The end of the cord remote from the latch lever 100 is secured to the post 62, and consequently upon initial movement of the post a pull will be exerted on the cord for swinging the latch lever 100. Any pull on the cord tends to move the latch pin 104 under the laterally extending keeper 92, and in order to hold the latch lever 100 against accidental swinging movement a leaf spring 106 is provided.

35 In order to create a slight pull on the cord 106' at all times, a weight 107' is connected to the cord. This also provides a slight slack in the cord so as to allow for the increased swinging movement of the lever 58 over the swinging movement of the latch 100.

40 This leaf spring 106 is secured at its outer end to one of the side walls of the casing, and the same is provided intermediate its ends with an arcuate bight portion 107. The shank portion of the eye 105 is disposed in the path of the spring 106, and as the shank portion rides into the arcuate bight portion of the spring, the same is guided thereby under the said laterally extending keeper arm 92.

50 The trip arm 103 of the latch lever 100 is disposed in the path of the pins 35 on the table 26 when the latch pin 104 is under the keeper arm 92, and consequently upon any turning movement of the table in either direction, the latch arm 100 will be swung on its pivot against the tension of the spring 106 for moving the latch pin from under the keeper arm 92, for a purpose which will be later set forth.

60 By referring to Figure 7 of the drawings, it can be seen that the rod 75 at this point of connection with the ball-carrier 74 is disposed in the path of the swinging dog 97. Upon the downward movement of the rod 75 and ball-carrier, the rod will swing the dog 97 inwardly against the tension of its spring 98, and after the carrier receives the balls from the run-way, and is returned to its normal elevated position, the rod 75 rides on the inclined lower face of the dog 97 and forces the dog and the latch lever 94 to the right (referring to Figures 7, 8, 13, and 14.) This is accomplished, due to the fact that the dog is prevented from swinging movement to the left by the stop pin 99. Swinging movement of the hook-latch lever 94 to the right will move the hook-shaped latch arm 93 from out of engagement

with the hook-shaped keeper 91. Obviously, when both of the latches 93 and 100 are moved from out of engagement with the keeper-plate, the gate is permitted to lower.

5 In order to prevent the balls from rolling off the run-way 83, when the gate is in its raised position, and when the ball-carrier is in its raised position, a resilient arm 107 is provided. This resilient arm 107 has one end secured to the bottom face of the run-way, and its opposite end is provided with an upstanding leg 108, which normally extends above the lower wall of the run-way. A laterally extending finger 109 is formed on the leg 108, and this finger 109 is arranged in the path of a ball-carrier 74, 15 so that upon downward movement of the carrier the arm will be depressed to move the leg 108 below the run-way.

20 Referring to the coin-controlled mechanism 84, it is to be noted that the same embodies a sliding plunger plate 110 mounted within a guide-way 111. This plunger plate 110 is coupled with a second plunger plate 112 when a coin of the desired denomination is inserted in the said plunger plate 110. The specific construction of the coin-controlled mechanism forms no part of the present invention, and may be of any desired construction provided that the plate 112 is moved inwardly upon operation of the plate 110. The post 62 is disposed in the path of the plate 112, 30 and thus when the plate is moved inwardly the post will be operated for swinging the lever 58. Connected with the plate 112 is a downwardly inclined arm 113, and the swinging arm 88 of the gate 85 is disposed in the path of the inclined arm 113. Consequently, when the plate 112 is moved inwardly, the inclined arm will depress the swinging arm 88, causing the raising of the gate to an elevated position, as shown in Figure 8 of the drawings. 40

25 In operation of our improved game, the coin of the called for denomination is inserted within the coin mechanism 84, and the plate 110 is pushed inwardly. This will move the plunger 112 inwardly and cause the swinging of the 45 lever 58, the rocking of the arm 88, and a pull on the cord 106'. Swinging movement of the lever 58 will allow the lowering of the table 26 so that any balls resting upon the same will be permitted to drop upon the baseboard 51. These 50 balls will roll into the run-way 83 and will be stopped by the resilient arm 107. The downward movement of the arm 88 will raise the gate 85 and synchronously with the raising of the gate the latch pin 104 will be moved under the keeper 55 arm 92 by the pull cable 106'. Upward movement of the gate 85 will position the keeper-hook above and in the path of the hook-shaped latch arm 93. Movement of the keeper-hook 91 past the latch lug is permitted, due to the resiliency 60 of the latch hook and wedge-shape of the keeper hook.

65 The game is now ready to be played, and the operator pushes down on the handle 80 so as to move the ball-carrier 74 in alignment with the run-way. As the ball-carrier reaches the run-way, the resilient arm 107 is flexed, which allows the balls to roll in the carrier. The carrier 74 is now returned to its normal raised position by 70 the operator, or by the spring 82. The balls can be shot one at a time by means of the plunger on to the race-way 27, and as the balls lose their momentum, the same will drop into one of the pockets 25. After all of the balls have 75

been played, the operator determines the best poker hand that can be made by drawing to the cards indicated by the balls in the pockets. Say a player has made three kings with his first 5 five shots and two off-cards. The player will then release the two balls indicating the off-cards. This is accomplished by grasping the handle 50 and turning the same until the pointer reaches the first ball that is to be released, after 10 which the finger-piece 49 of the plunger rod 43 is pressed downwardly. This will move the gate 37 of the table 28 inwardly, and the ball will drop on to the base-board and gravitate into the run-way. The second ball is released in the 15 same manner. As soon as the handle 50 is turned, the pins 35, moving with the table, strike the trip arm 103 of the latch lever 100, causing the movement of the pin 104 from under the keeper arm 92. This allows the gate to drop a short 20 distance until the keeper hook 91 engages the latch hook 93. So far it can be seen that the initial or primary latch has been released. The player again moves the carrier 74 downwardly to receive the two balls that have been released, 25 and as the carrier returns to its normal raised position, the latch lever 94 is swung to the right, as heretofore described, moving the latch hook 93 from out of engagement with the keeper hook 91. As the gate is no longer held in its raised 30 position by the latch pin 104, the gate will immediately drop to its closed position, as shown in Figure 14 of the drawings. The two balls in the carrier can now be projected on to the race-way to see if the hand can be bettered. This 35 constitutes one game, and as the gate is in its lowered position, the game cannot be played again until the plunger 112 is moved inwardly.

In order to prevent the jamming at the run-way, and to insure the entrance of the balls 40 into the run-way, we provide a swinging pusher finger 115 which is disposed adjacent to the entrance of the run-way. This swinging pusher finger 115 is rigidly connected to a shaft 116 rockably mounted on the walls of the run-way. Connected to the hub portion of the pusher finger 45 is a crank arm 117 to which is connected a link 118, which is in turn connected to the crank arm 81 of the rod 75 of the ball-carrier 74. Thus it can be seen that upon movement of the ball-carrier swinging movement will be imparted to 50 the pusher finger.

From the foregoing description, it can be seen that we have provided a novel game, which will afford a maximum amount of pleasure and interest to the players thereof.

Changes in details may be made without departing from the spirit of the scope of this invention, but what we claim is:—

1. A game comprising a game board, ball trapping means associated with the game board, means for projecting balls over the board whereby the same can fall by chance into said ball-trapping means, means for simultaneously releasing all of the trapped balls, and independent means for selectively releasing undesired trapped balls.

2. A game comprising a casing, an annular race-way disposed in said casing, a disc-shaped game board arranged axially within the race-way, means for supporting the game board, radially projecting pins carried by the game board and extending towards the race-way defining ball-receiving spaces, a rotatable table mounted below the game board and projecting under said pins for supporting the balls, means for pro-

jecting the balls over the race-way and toward said pins, manual means for rotating the table, a sliding gate carried by the table movable under any adjacent pair of selected pins during rotation of the table, and means for actuating the gate.

3. A game comprising a casing, a game board disposed in the casing, a race-way surrounding the board and inclined toward the board, radially projecting pins carried by the board extending toward the race-way and defining ball-receiving spaces, means for projecting balls over the race-way, a table arranged below the board and projecting under the pins for supporting the balls, means for bodily moving the table in a horizontal plane for simultaneously releasing all of said balls, and independent means carried by the table for selectively releasing the balls.

4. A game comprising a casing, a game board in said casing, a race-way surrounding and inclining toward the game board, pins carried by the board and projecting toward the race-way defining ball-receiving spaces, a table arranged below the board and projecting pins for supporting balls trapped between the pins, means for projecting the balls over the race-way, a hollow shaft extending through the board rotatably supporting the table, a handle on the shaft for turning the table, a radially projecting gate slidably supported by the table and movable under any adjacent pair of selected pins, and means for operating the gate including a plunger rod slidably carried by the hollow shaft and terminating above said shaft.

5. A game comprising a casing, a game board disposed in the casing, a race-way surrounding and inclining toward the board, means for projecting balls over the race-way, a plurality of pins carried by the board projecting toward the race-way defining ball-receiving spaces therebetween, a rotatable table disposed below the board and projecting under the pins for supporting the balls, a hollow shaft rotatably and slidably carried by the board, releasable means for bodily supporting the table, means for rotating the table, and a manually releasable gate movable toward the axis of the table and inward of the periphery thereof.

6. A game comprising a casing, a game board supported within the casing, an annular race-way surrounding and inclining toward the board, means for projecting balls on the race-way, a plurality of radially projecting pins carried by the board extending toward the race-way defining ball-receiving spaces therebetween, a table arranged below the board and projecting under said pins for supporting the balls, a hollow shaft connected with the table rotatably and slidably supported by said board, means disposed exteriorly of the casing for rotating the shaft, a yoke secured to the lower face of the table, an operating lever rockably mounted on the table having a wedge-shaped shoe movable into and out of engagement with the yoke for bringing about the raising and lowering of said table, a radially movable gate on said table, and manual means for sliding the gate toward the axial center of the table and inward of the periphery of said table.

7. In a game, a casing, a game board supported within the casing, an annular race-way surrounding and inclining toward the board, a plurality of radially projecting pins carried by the board and extending toward the race-way defining ball-receiving spaces therebetween, a

table disposed under the board and extending under said pins for supporting balls received between adjacent pairs of the pins, said table being movable up and down toward and away from the board, means for projecting balls over the race-way, and means for raising and lowering the table for releasing the balls received between said adjacent pairs of pins.

8. In a game, a casing, a game board supported within the casing, an annular race-way surrounding and inclining toward said board but spaced therefrom, means for projecting balls over the race-way, a plurality of radially projecting pins carried by the board and extending toward the race-way defining ball-receiving spaces therebetween, a table movable up and down disposed under the board and extending under said pins for supporting balls received between adjacent pairs of the pins, coin-controlled means for raising and lowering the table for simultaneously releasing all the balls received between adjacent pairs of pins, and manually actuated means associated with the table for selectively releasing the desired balls from between any desired pair of said pins.

9. In a game, a playing surface having ball-trapping means associated therewith, means for projecting balls over the playing surface toward said ball trapping means, means for simultaneously releasing all of the trapped balls, independent means for selectively releasing the desired trapped balls, a run-way for receiving the released balls, a gate for controlling the movement of the balls from the run-way, a ball-carrier movable from the run-way to the ball-projecting means, coin-controlled means for simultaneously raising the gate and for actuating the means for simultaneously releasing all of said balls, a pair of latches for holding the gate in a raised position, means actuated by the selective ball-releasing means cooperating with one of said latches, and means operated by the ball-carrier for releasing the other of said latches.

10. In a game, a ball-playing surface having ball-trapping means associated therewith, means for projecting balls over said surface toward said ball trapping means, means for simultaneously releasing all of the trapped balls, independent means for selectively releasing the desired trapped balls, a run-way inclined toward one side of the casing for receiving the released balls, a resilient detent normally preventing movement of the balls from off of the run-way, a manually actuated swinging ball-carrier movable to the run-way for receiving the balls therefrom, said resilient detent being in the path of the carrier whereby the same will be moved below the run-way upon downward movement of the carrier, said carrier being normally in alignment with the ball-projecting means for delivering balls thereto, a swinging gate for normally preventing movement of the balls from off of the run-way, coin-controlled means for simultaneously raising the gate and for actuating the means for simultaneously releasing the balls from the playing surface, a pair of latches for holding the gate in a raised position, means operated by the selective ball-releasing means for actuating one of the latches, and means operated by the ball-carrier upon movement thereof for releasing the other of said latches.

11. In a game, a ball-playing surface having ball-trapping means associated therewith, means for projecting balls over said surface toward said trapping means, means for simultaneously re-

leasing all of the trapped balls, independent means for selectively releasing the desired trapped balls, a run-way inclined toward one side of the casing for receiving the released balls, a resilient detent normally preventing movement of the balls from off of the run-way, a manually actuated swinging ball-carrier movable to the run-way for receiving the balls therefrom, said resilient detent being in the path of the carrier whereby the same will be moved below the run-way upon downward movement of the carrier, said carrier being normally in alignment with the ball-projecting means for delivering balls thereto, a swinging gate for normally preventing movement of the balls from off of the run-way, coin-controlled means for simultaneously raising the gate and for actuating the means for simultaneously releasing the balls from the playing surface, a pair of latches for holding the gate in a raised position, means operated by the selective ball-releasing means for actuating one of the latches, means operated by the ball-carrier upon movement thereof for releasing the other of said latches, and means operated from the ball carrier for feeding the balls down the run-way.

12. In a game, a casing, a playing board in said casing, a race-way surrounding and inclining toward said board, radially projecting pins carried by the board extending toward the race-way and defining ball-receiving spaces therebetween, a table disposed below the board projecting under said pins for supporting balls trapped between adjacent pairs of the pins, means rotatably and slidably supporting the table, means for rotating the table, a sliding gate carried by the table, means for moving the gate inwardly of the periphery of the table for selectively releasing desired trapped balls, a run-way for receiving balls released from the table, a swinging gate normally preventing movement of the balls from off of the run-way, a means for projecting balls over the run-way, a swinging carrier movable into alignment with the run-way for receiving balls therefrom and into alignment with the ball projecting means, coin-controlled means for simultaneously raising the swinging gate and for lowering the table for simultaneously releasing all of said trapped balls, a latch plate connected with the swinging gate, a swinging latch lever engaging the plate, means for operating the swinging latch lever upon rotation of the table, a second latch lever engaging the latch plate, a pivoted latch plate supporting the last-mentioned latch lever, a pivoted dog connected to the latch plate, means limiting the swinging movement of the dog in one direction, and spring means resisting the movement of the dog in the other direction, and said dog being in the path of the ball carrier whereby to bring about actuation of the latch plate upon movement of the carrier in one direction.

13. In a game having playing cards, game pieces for selecting playing hands from said cards, means for playing the game pieces, player-controlled means for selectively discarding the game pieces not desired in the playing hand, means for re-playing the discarded game pieces, whereby additional cards for said hand can be selected upon reactuation of said means for playing the game pieces, and mechanical means preventing re-playing of game pieces after the discarded game pieces have been re-played.

14. In a game having counting pockets, game pieces for movement into said pockets, means for actuating the game pieces, player-controlled means for selectively discarding the game pieces

not desired in the counting pockets to permit the re-playing of said discarded game pieces, mechanical means preventing the re-playing of the game pieces after the discarded game pieces have been re-played, and means for releasing said mechanical means.

15. A game comprising a game board, game piece trapping means associated with the board, means for projecting the game pieces over the board for movement into the trapping means, means for selectively releasing game pieces not desired, independent means for releasing all of the game pieces, latch-controlled means for governing the movement of the game pieces to the

projecting means, and means for releasing the latch-controlled means upon operation of the selective releasing means and the game piece projecting means.

16. A game comprising a game board, ball-trapping means associated with said game board, means for projecting balls over said game board whereby the same can fall by chance into the ball trapping means, and a releasable gate movable under any selected ball-trapping means for releasing an undesired ball therefrom to permit the re-playing of said ball.
